UNITED STATES PATENT OFFICE.

WALTER G. E. ROLAFF, OF BELLEVILLE, ILLINOIS.

ROTARY-PISTON PACKING.

1,358,176.

Specification of Letters Patent.

Patented Nov. 9, 1920.

Application filed August 4, 1919. Serial No. 315,191.

To all whom it may concern:

Be it known that I, WALTER G. E. ROLAFF, a citizen of the United States, residing at Belleville, in the county of St. Clair 5 and State of Illinois, have invented new and useful Improvements in Rotary-Piston Packing, of which the following is a specification.

This invention relates to rotary machines, 10 such as air compressors, rotary engines, pumps, or any other rotary machine operating with a fluid. The invention is particularly applicable to rotary machines of the type in which a drum, or rotor, rotates with- 15 in a barrel or cylinder and carries a piston which touches the inner face of the cylindrical shell and the heads. It is necessary to provide means for packing the piston in order to prevent leakage. The line of contact of the piston with the shell may be 20 packed very readily, but it is more difficult to pack the ends of the piston where they touch the heads of the barrel.

The general object of the present invention is to provide improved means for packing a rotary machine of this type. In one aspect, the invention may be regarded as an improvement of the rotary piston packing disclosed in my Patent No. 1,280,309, dated 25 October 1, 1918. The packing means disclosed in the patent referred to above involves the use of over-lapping plates, which by reason of this construction were made relatively thin. As these relatively thin 30 plates project at times a considerable distance past the periphery of the drum, an element of weakness is present in such a construction; one of the objects of the present invention is to overcome this defect and to 35 provide a rotary piston packing of simple construction which will operate effectively 40 to insure effective packing of the piston at the heads of the barrel without necessitating the weakening of the packing means or 45 plates by reducing their thickness as referred to above.

My invention operates in such a way that I utilize the relatively high fluid pressure existing within the rotary machine to press 50 the packing members of the piston firmly against the heads.

Further objects of the invention will appear hereinafter.

The invention consists in the novel features, and in the general combination of parts to be particularly described herein-

after, all of which contribute to produce a simple and efficient rotary piston packing. A preferred embodiment of my invention will be particularly described in the following specification, while the broad scope of my invention will be pointed out in the appended claims. 60

In the drawing,

Figure 1 is a vertical cross-section through 65 a rotary machine embodying my invention;

Fig. 2 is a longitudinal vertical section;

Fig. 3 is a horizontal cross-section on the line 3—3 of Fig. 2, and

Fig. 4 is a rear elevation showing details 70 of the construction.

The rotary machine to which I have illustrated my invention as applied, comprises a barrel having a cylindrical shell 1, and substantially flat heads 2; within this barrel 75 there is rotatably mounted a drum 3, carried by a shaft 4, which cooperates with the barrel to form a chamber 5; in the present instance this chamber is formed by mounting the drum eccentrically in the barrel in a well 80 known manner. The drum carries a piston 6 which is preferably of blade form, having means so constructed that when acted upon by the fluid pressure on the working side of the piston, the force exerted by the fluid 85 under pressure will press the packing members against the heads. In order to accomplish this, I prefer to construct piston blade 6 with a main plate, or section 8 disposed between packing members or plates 7 disposed 90 respectively adjacent to each head 2.

This plate and the packing members 7 are mounted to slide freely in and out in a piston guide-opening 9, which is formed substantially radially in the drum. The direction of rotation of the drum is indicated by the arrows in Figs. 1 and 3, so that the forward lateral face or side 10 of the piston 6, with respect to the direction of rotation, which is exposed to relatively high fluid 100 pressure, is to be considered the "working side" of the piston.

I construct the piston blade in such a way that the force exerted by the fluid under pressure operates to force the packing members 7 out against the heads 2. I accomplish this in a very simple manner, preferably by constructing the piston blade 6 in such a way that the main plate or main section 8, and the packing members are so correlated 105 that the main plate will operate as a wedge plate, that is to say, it reacts against the

pressure of the packing members 7 and forces the packing members outwardly; for this purpose the packing member 7 and the plate 8 are provided with meeting faces 11, which are inclined with respect to the plane of the blade, that is to say, they lie in a plane passing from the forward or working side of the blade to the rear side of the blade (see Fig. 3); in this way, the packing 10 members form a flexible scarf-joint or sliding joint with the main plate. As the meeting faces are thoroughly oiled, it is evident that when the relatively high fluid pressure in the chamber 5 exerts itself on the working 15 side of the blade, that is to say, upon the working side of the packing members 7, they will tend to slide in an outward direction on account of the inclination of the faces 11; in doing this, the plate 8 will act 20 as a reaction wedge, as it were.

In order to insure efficient operation of the piston blade 6, and also to prevent the packing members 7 from slipping out by themselves under the action of the centrifugal force, in case the main plate should stick and not move outwardly when it should, I prefer to provide means for limiting the movement of the packing members with respect to the main plate. This means 30 permits a limited amount of movement only and, preferably, consists of a pin 12 corresponding to each packing member carried by the plate 8, said pin projecting into a slightly enlarged opening 13 in the corresponding packing member.

The direction of rotation is indicated by the arrows in Figs. 1 and 3. These rotary machines run at a relatively high speed, so that the centrifugal force acting upon the 40 blade 6, will insure efficient packing of the outer edge of the blade, that is to say, it will pack the line of contact between the blade and the shell. By reason of the inclined faces 11, the packing members will 45 also pack the line of contact between the ends of the blade and the heads 2.

Referring to Fig. 1, which illustrates the invention as applied to a compressor, it will be evident that as the piston blade 6 traverses the chamber 5, it will produce a partial vacuum behind it, drawing in the air at the inlet 14^a, which will be compressed in front of the piston which will finally force the air out through the outlet valve 14^b from 55 which the compressed air will pass to a suitable accumulator or reservoir.

I provide means for eliminating the compression of the fluid, or air, which might take place at the inner end of the guide-opening 9, and I also provide means for balancing or counter-balancing the pressure of the fluid on the working face and rear face of the blade lying within the guide-opening 9. In order to accomplish this, I 60 construct the blade and the drum in such

a way that they will coöperate to admit the fluid under pressure from the chamber 5 adjacent to the working side 10 of the blade, into the inner end of the guide-opening 9. In order to accomplish this, I simply provide a plurality of small grooves 15, which I cut in the forward face of the guide-opening, (with respect to the direction of rotation), and I also provide an equalizing chamber 16 on the rear side of the blade. 75 This is formed by cutting a recess in the rear face of the guide-opening and providing communication between this equalizing chamber and the inner end of the guide-opening. I also prefer to provide a wide 80 rectangular shallow channel 17 in the rear side of the blade, that is, in the main plate 8, which operates to increase the volume of the equalizing chamber 16 and also results in producing a wearing rib 18 at the inner 85 end of the plate which bears against the rear face of the guide-opening 9. Through this rib 18, I cut a recess, or notch 19, which maintains constant communication between the inner end of the guide opening 9 and the equalizing chamber. If desired, I may also provide an opening 20 through this plate which opens communication between the air films on the opposite sides of the 90 plate 8 in the guide-opening. 95

With this organization of parts, it is evident that the relatively high fluid pressure which is developed on the working side of the blade, will be admitted to both faces of the piston blade so that the pressure forces acting on these two faces are substantially equalized. There is however, a slight excess of force on the working side of the blade within the guide-opening 9 by reason of the existence of the bearing area 105 of the rib where the blade bears against the rear faces of the guide-opening; another unbalanced area exists: In order to pack the equalizing chamber to prevent escape of the fluid under pressure to the portion 110 of the chamber 5 which lies adjacent to the rear side of the blade, I provide a wear-strip 21 which is preferably formed of hardened steel and which is counter-sunk in the face of the guide-opening.

When this piston packing is employed on a rotary steam engine instead of on a compressor, of course the "working side" of the blade would be the rear side instead of the forward side, as in a compressor. However, in either case, I utilize the working pressure exerted upon the side face of the blade to effect the holding of the packing members against the heads of the cylinder.

It is understood that the embodiment of the invention described herein is only one of the many embodiments my invention may take, and I do not wish to be limited in the practice of my invention nor in my claims, to the particular embodiment set forth.

What I claim and desire to secure by Letters Patent is:

1. In a rotary machine operating with a fluid, the combination of a barrel having a cylindrical shell, and heads, a drum rotatably mounted within the barrel and coöperating therewith to form a chamber, a piston blade carried by the drum and traversing said chamber so that a relatively high fluid pressure is developed in the latter on the lateral face of the blade, said blade including a packing member disposed against each head, and including means whereby the fluid pressure exerted upon the said lateral face of the blade forces the packing members against said heads. 5
2. In a rotary machine operating with a fluid, the combination of a barrel having a cylindrical shell, and heads, a drum rotatably mounted within said barrel and coöperating therewith to form a chamber, a piston blade carried by the drum and traversing the chamber so that a relatively high fluid pressure is developed in the latter on the lateral face of blade, said blade including a packing member disposed against each head and a wedge plate engaging the packing members, and reacting under the action of the fluid pressure exerted against the side 10 of the blade to force the packing members against the heads. 15
3. In a rotary machine operating with a fluid, the combination of a barrel having a cylindrical shell, and heads, a drum rotatably mounted within the barrel and coöperating therewith to form a chamber, a piston blade carried by said drum and traversing said chamber so that a relatively high fluid pressure is developed in the chamber on the working side of the blade, said blade including a packing plate disposed against each head and a plate between said packing plates, said last named plate and said packing plates having meeting faces disposed in 20 a plane inclined to the middle plane of said blade, whereby, the fluid pressure exerted upon the forward side of said packing plates operates to force the packing plates against the heads. 25
4. In a rotary machine operating with a fluid, the combination of a barrel having a cylindrical shell, and heads, a drum rotatably mounted within said barrel and coöperating therewith to form a chamber, a piston blade carried by said drum and traversing the chamber so that a relatively high fluid pressure is developed in the latter on the working side of the blade, said blade including a packing plate disposed against each head 30 and a main plate disposed between said packing plates, said main plate and the packing plates having meeting faces disposed in a plane inclined to the middle plane of the blade and passing from the driving side to the rear side of said blade, said plates 35
- coöperating under the action of said fluid pressure exerted against the side thereof to force the packing plates against said heads. 40
5. A rotary machine constructed as specified in claim 1, in combination with means for limiting the movement of said packing members. 70
6. A rotary machine constructed as specified in claim 2, in combination with means for limiting the movement of said packing members with respect to the wedge plate. 75
7. In a rotary machine operating with a fluid, the combination of a barrel having a cylindrical shell, and heads, a drum rotatably mounted within said barrel and coöperating therewith to form a chamber, a blade carried by said drum and movable in and out to maintain contact with said cylindrical shell and traversing said chamber so that a relatively high fluid pressure is developed 80 in said chamber on the forward side of said blade, with respect to the direction of rotation, said blade including a packing member disposed against each head and including means whereby the said fluid pressure acting 85 upon the forward side of said packing members forces the said members against said heads, and means for admitting the fluid under pressure to the rear side of the blade within the drum to counter-balance the force 90 of the fluid pressure acting on the forward side of the blade. 95
8. In a rotary machine operating with a fluid, the combination of a barrel having a cylindrical shell, and heads, a drum rotatably mounted within said barrel and coöperating therewith to form a chamber, said drum having a piston blade guide-opening, a piston blade carried by said drum and movable in and out in said guide-opening 100 to maintain contact with said cylindrical shell, and traversing said chamber so that a relatively high fluid pressure is developed in said chamber on the forward side of said blade with respect to the direction of rotation, said blade including a packing member disposed against each head and including means whereby the fluid pressure acting 105 upon the forward side of said packing members forces the packing members against the heads, the wall of said guide-opening having an equalizing chamber adjacent the rear side of said blade, and means for admitting the fluid under pressure to the said equalizing chamber to counter-balance the 110 force of the fluid pressure acting on the forward side of the blade. 115
9. In a rotary machine operating with a fluid, the combination of a barrel having a cylindrical shell and heads, a drum rotatably mounted within said barrel and coöperating therewith to form a chamber, said drum having a piston guide-opening, a piston blade carried in said guide-opening and movable in and out therein to maintain con- 120 125 130

tact with said shell and traversing said chamber so that a relatively high fluid pressure is developed in said chamber on the forward side of blade, with respect to the direction of rotation and including a packing member disposed against each head, and also including means whereby the said fluid pressure exerted upon the forward side of said packing members forces the packing members against said heads, said guide-opening and said blade being constructed so that they coöperate to admit the relatively high fluid pressure to both sides of said blade within said guide-opening and thereby substantially balance the forces acting on the opposite sides of said blade.

10. In a rotary machine operating with a fluid, the combination of a barrel having a cylindrical shell and heads, a drum rotatably mounted within said barrel and coöperating therewith to form a chamber, a piston blade carried by said drum and movable in and out to maintain contact with said cylindrical shell and traversing said chamber so that a relatively high fluid pressure is developed in said chamber on the forward side of the blade, said blade with respect to the direction of rotation including a packing member disposed against each head and 30 including means whereby said fluid pressure exerted upon the working side of said members forces the said packing members against the heads, the said drum having a guide-opening in which said blade moves, 35 the inner end of said guide-opening being in communication with the interior of the chamber adjacent to the forward side of said blade to eliminate compression therein

during the inward movement of said blade, said guide-opening also having an equalizing chamber on the rear side of said blade, said blade and drum coöperating to admit the fluid under pressure to the said equalizing chamber and to the forward side of the blade within said guide-opening whereby the pressure forces acting upon opposite sides of said blade within said guide-opening are substantially balanced.

11. In a rotary machine operating with a fluid, the combination of a barrel having a cylindrical shell, and heads, a drum rotatably mounted within said barrel and coöperating therewith to form a chamber, a piston blade carried by said drum and traversing said chamber so that a relatively high fluid pressure is developed in said chamber on the working side of the blade, said piston blade including a packing member disposed against each head and a plate having a flexible scarf joint with each of said packing-members, and operating as a wedge under the action of the said fluid pressure upon the driving side of the packing members to force said packing members against said heads.

12. A rotary machine constructed as specified in claim 4, in combination with a pin carried by said main plate corresponding to each of said packing plates, each of said packing plates having an enlarged opening receiving its corresponding pin and permitting a limited movement of said packing plates relatively to said main plate.

In testimony whereof, I have hereunto set my hand.

WALTER G. E. ROLAFF.
